UNITED STATES PATENT OFFICE.

WALTER JAMES HILL, OF BIRMINGHAM, ENGLAND.

EXTENSIBLE HINGE OR FASTENING.

Application filed April 22, 1926, Serial No. 103,823, and in Great Britain February 11, 1926.

This invention is for improvements in or relating to extensible hinges and fastenings for trunks, suit cases, sample cases, attaché cases, and like receptacles of variable capacity governed by relative sliding adjustment of a complementary pair of boxlike component parts of the receptacle adapted to telescope one within the other.

The type of hinge or fastening to which 10 the invention relates is that which comprises a two-part telescopic member carried by the one part of the receptacle, and a hinged member, which may be either a rear hinge plate or a front hasp, carried by the sliding 15 inner part of this telescopic member and adapted for attachment to or engagement with the other part of the receptacle, the parts of said telescopic member being adapted, when the receptacle is closed, to be 20 locked together in any adjusted position by means actuated by the angular closing movement of the hinged member.

According to the present invention an extensible hinge or fastening of the type referred to is provided in which the locking of the relatively sliding parts of the telescopic member is effected by means of a rocking lever catch pivotally mounted within the sliding inner part so as to be engageable with a rack provided within the back 25 of the fixed outer casing part of the telescopic member, the angular movement of this rocking lever catch being governed in accordance with the angular position of the hinged member by means of a heelpiece on 30 said hinged member arranged in engagement with the outer extremity of the catch lever, and by means of a spring arranged to rearwardly depress the inner extremity of 40 the catch lever.

In order that this invention may be clearly understood and readily carried into practice, reference may be had to the appended explanatory sheets of drawings upon 45 which:—

Figure 1 is a front elevation of an extensible hasp fastening in accordance with the invention, the same being shown in its contracted and fastened position of use.

50 Figure 2 is a side elevation of Figure 1, partly in section.

Figure 3 is a front perspective view of the fixed outer casing of the two-part telescopic member, the same being partly broken away.

55 Figure 4 is a rear perspective view of the

inner slide of the two-part telescopic member.

Figure 5 is a sectional side elevation of the extensible hasp fastening, the same being shown in its contracted and released position.

Figure 6 is a front perspective view of an extensible hinge in accordance with the invention, the same being shown in its released, and partly extended position.

Figure 7 is an end elevation of a trunk or case fitted with the extensible hinges and fastenings in accordance with the invention, the trunk or case being shown in its contracted adjustment.

Figure 8 is a similar view of the trunk or case in an extended position of adjustment.

In a convenient embodiment of the invention, the extensible hinge or fastening comprises a two-part telescopic member 1, 2, 55 adapted to be secured to the one boxlike component part 3 of the telescopic case or receptacle, and a hinged member, which may be either a hinge plate 4 for the rear of the receptacle or a hasp 5 for the front of the receptacle, carried by the outer end of the sliding inner part 2 of the telescopic member, and adapted for attachment to or engagement with the other boxlike part 6 of the receptacle.

The telescopic member comprises a fixed outer casing 1 of elongated rectangular form, and an inner slide 2 accommodated therein. The casing 1 is preferably of sheet metal construction, with a separately formed back 7, and is provided on each side with projecting lugs 8 apertured for accommodation of attachment screws or rivets 9, the back 7 of the casing being provided with a central longitudinal rack 10 formed for instance by perforating said back and by inwardly pressing the intervening transverse strips of metal to constitute inclined rack teeth.

The inner slide 2 is of elongated channel form, and at an intermediate point in its length it is apertured to provide bearings for a transverse pivot pin 11. Upon this pin 11 is pivotally mounted, also at an intermediate point in its length, a rocking lever 12 of strip metal construction, this lever 12 being enclosed within the channel-shaped slide 2. The inner extremity of the rocking lever 12 is formed with a rearwardly turned lip 13 which constitutes a terminal

catch adapted for engagement with the rack 10 on the back of the casing, and a blade spring 14 is interposed between this end of the catch lever 12 and the inner face of the slide 2, this spring 14 being riveted or otherwise secured at one end as at 15 to the catch lever, and tending to rearwardly depress the catch 13 into engagement with the rack 10. The inner end of the catch lever 12 is cut 10 away longitudinally along each edge so as to be of reduced width, and this reduced end 16 is rearwardly cranked towards the back of the casing, the bearing lugs 17 for the catch lever 12 being formed by rearwardly overturning the cut-out longitudinal edges of the strip into cylindrical form.

The outer end of the slide 2 is transversely apertured for accommodation of a hinge pin 18 upon which is mounted the hinged member 20 of the fastening, which hinged member may be either a rear hinge plate 4 or a front hasp 5, this hinged member having a small rearwardly projecting heelpiece 19 adapted for engagement with the cranked outer extremity 16 of the rocking catch lever 12, the arrangement being such that when the case or receptacle is closed, and the hinged member is disposed in alignment with the telescopic member, the heelpiece 19 of the hinged member is held clear of the catch lever 12 and the catch 13 is rearwardly depressed by the action of its blade spring 14 to hold the catch in locking engagement with the rack teeth 10, as shown in Figure 2, to thereby securely retain the relatively sliding parts of the telescopic member against expansive movement in any position in which they may have been adjusted. On the hinged member being moved into angular relation to the telescopic member, when the case or receptacle is opened, the heelpiece 19 of the hinged member is brought into engagement with the cranked outer end 16 of the catch lever 12 to rearwardly depress this end of the lever, the lever 12 being thereby rocked against the action of its blade spring 14 and released from its locking engagement with the rack 10, as shown in Figure 5, thereby permitting of any desired re-adjustment of the extensible hinge or fastening when the case or receptacle is to be again packed and closed. The outward adjustment of the in-

ner slide 2 in relation to the outer casing 1 may be limited by suitable stops provided on 55 the outer casing.

The case or receptacle is preferably fitted with a pair of the extensible hinges in the rear, and with a pair of the extensible hasp fastenings in front. On the hasps 5 being 60 released from their fastened engagement with the usual lock members 20, the outer part 3 of the case or receptacle is free to be opened on its hinges as shown in dotted lines in Figures 7 and 8, in which position the 65 catches 13 of the extensible hinges and fastenings are released to permit of longitudinal adjustment of the two-part telescopic members of the hinges and fastenings, and to thereby provide the desired variation in 70 the capacity of the case or receptacle according to the quantity of articles to be packed therein. On the case or receptacle being then closed, it may be secured in an extended or partly extended position as 75 shown in Figure 8, in which position it is locked against any further expansive movement, whilst remaining free to be further contracted by pressure on the top of the case or receptacle to ensure tight packing, this 80 further contraction being permitted by the inclined formation of the rack teeth 10, which are slidable freely in one direction over the catches 13.

What I claim as my invention and desire 85 to secure by Letters Patent is:—

For use with a trunk, case, or other receptacle of variable capacity, an extensible member comprising an outer casing adapted to be carried by the one part of the receptacle, a slide within said casing, a hinged member carried by said slide and adapted for attachment to or for fastening engagement with the other part of the receptacle, a rack provided within the back of said casing, a rocking catch lever pivotally mounted within said slide and adapted to engage said rack, a spring operating to normally hold said catch in engagement with said rack, and a heelpiece on said hinged member adapted to engage the extremity of said catch lever for releasing the same from engagement with said rack.

In witness whereof I have hereunto set my hand.

WALTER JAMES HILL.
